REGISTRATION INDICATOR FOR WEB
TREATING APPARATUS

Morris Sorkin, Teaneck, N. J., assignor, by mesne assignments, to Interchemical Corporation, New York, N. Y., a corporation of Ohio

Application November 17, 1938, Serial No. 240,899

14 Claims. (Cl. 177—311)

This invention relates to high speed multi-color printing and aims to provide an improved mechanism for indicating when the web is out of register in the direction of its travel.

In modern high speed printing, where the web is to be imprinted with a plurality of colors or the printed web is to be cut subsequently into individual sheets, it is essential to maintain accurate registration between successive operations. Due to the speed at which the web travels, it is not possible for the human eye to follow it for a sufficient length of time to check registration. Accordingly, various devices have been proposed for controlling registration automatically by means of photo-electric cells and other cooperating mechanism. Such devices, however, are of a complex nature and it has been impossible to render them universally effective for both large and small increments of correction. That is, when the press is first started, large corrections are usually necessary, and if the apparatus will take care of these, it will not be sensitive enough to make the desired small corrections during normal operation; while if the apparatus is set for the small increments of correction, it does not function properly for the large corrections needed when the press is first started. Furthermore, certain of these devices have included rotating switches or contacts, operating in timed relation with the printing cylinders for making connections with the electric circuits, and these require frequent adjustment and are a constant source of trouble.

In order to overcome these and other difficulties, it has been suggested that the actual adjustments in registration be made manually upon the operation of a suitable indicating mechanism. One form of indicator that has been provided includes two photo-electric circuits where one photo-cell is directed upon a target applied to a moving web and the second is controlled by the light change caused by a target or mark provided on a rotating element of the press. Such an indicator is shown in Shoults et al. Patent No. 2,151,570, dated March 21, 1939. The circuits associated with the photocells have included four thyratron tubes and a timing circuit including still another thyratron, a rectifier and transformer. While the apparatus has functioned satisfactorily, it has been, in all, rather complicated and expensive, particularly when it is used in conjunction with a four or five color press and the circuits are duplicates for each color unit after the first.

I have discovered that such circuits may be

modified in certain fundamental aspects so as to render the resulting apparatus completely flexible, easy of adjustment and much cheaper than any other circuit heretofore provided.

5 In accordance with my invention the third and fourth thyratrons and the complicated timing circuit are entirely eliminated, and in their stead relays and a timing triode are interconnected with the remaining circuits. Thus, the two photo-cells are included in circuits which comprise suitable amplifiers, thyratrons, relays, a timing vacuum tube and associated relay, and two indicator lamps, one for indicating when the web is advanced and the other for indicating when the web is retarded. Also included in the circuits is a greatly simplified tolerance control. Furthermore, I have found that initial adjustments of the apparatus are greatly simplified and rendered more accurate by the inclusion of a diode tube 10 between the first and second thyratrons, so as to limit the amplitude of the pulse impressed on the grids of said thyratron. The entire arrangement of the circuits and electrical devices included therein is such that when the targets for each photo-cell give their effect simultaneously, neither indicator lamp will be operated; whereas if the web is out of register, there will be a time interval between the actuation of each photo-cell which will cause the proper indicator light 15 to be operated and flash its signal to the attendant as long as the web remains out of register.

The above and other features of the invention will become apparent upon consideration of the following detailed description of one practical embodiment thereof, and the accompanying drawing in which:

20 Fig. 1 is a diagrammatic perspective representation of a plurality of color units of a multi-color printing press equipped with a registration indicator embodying my invention; and

Fig. 2 is a diagrammatic showing of various electrical circuits and devices used in conjunction with the two photo-cells and indicator lights, and including my improvements.

25 I have shown the invention applied to a multi-color printing press, such for example as is disclosed in Arthur M. Wickwire, Jr. Patent No. 2,278,387, dated March 31, 1942, and in the patents and applications referred to therein. It will be understood, however, that the invention is not restricted in its use to printing machines of any particular type but may be used in printing machines generally and in packaging machines, cutting machines and the like where it is necessary 30 to maintain the moving web in definite register.

Referring now to the drawing, it will be observed that a web 10 is fed through a multi-color printing press including a first color unit 12, a second color unit 14 and a third color unit 16, so that as said web is fed therethrough, it may be printed in three colors, or as many more colors as there are printing units. It is of course necessary that all imprints applied to the web after the first imprint be in register therewith. However, due to changes in the tension of the web as it passes between units and unavoidable inaccuracies in feeding, errors in register often occur in the second and subsequent imprints. When the various units are equipped with suitable register control gearing, such as that disclosed in William F. Grupe Patent No. 2,163,035, dated June 30, 1939, corrections can readily be made as soon as the operator is made aware that they are necessary.

For notifying the press attendant when a correction or adjustment is required the press may be equipped with a registration control indicator of the type disclosed in the Shoultz et al. Patent No. 2,151,570 referred to above. In using such an indicator the first color unit 12 is arranged to print an index signal or target 18 on the web, and indicators are provided at each of the subsequent printing units 14 and 16. As part of the indicating apparatus associated with the second color unit 14, for example, there is included a suitable light sensitive device 20, such as a photo-electric or selenium cell, which is arranged in a scanning head (not shown) and conveniently mounted on the press so as to receive light impulses from the target 18. A second light sensitive device 22, such as a photo-electric cell, is also included in the indicating apparatus and adapted to receive light impulses from a suitable target or mark 24 applied to a part of the press which is rotating in timed relation with the movement. I have shown the mark 24 applied to the printing cylinder of the second color unit but it will be apparent that such a mark could also be applied to the handwheel, shaft or other rotating element of the press.

The electrical circuits and electrical devices associated with the two photocells for any particular printing unit have included therein two conveniently located signal or indicator lamps 28 and 30 respectively, and said circuits are so arranged that when the photocells are actuated simultaneously, indicating that the impressions are in register at the second color unit, neither of the signal lamps will be lighted. If, however, the photocell for the handwheel is actuated prior to that for the web, the lamp 28, which may be colored red, will be lighted to signify to the attendant that the web is retarded and that the register control should be given a backward movement. Should the target on the web interrupt the beam of light for the photocell 20 before the handwheel photocell is actuated, the other signal lamp 30, which may be colored green, will be lighted to indicate that the web is too advanced so that the register control should be given a forward adjusting movement. Whenever either signal lamp is lighted it will continue to flash its signal to the attendant until the proper adjustment is made. All of the electrical control apparatus, with the exception of the scanning heads may be conveniently housed in a cabinet 26, as indicated in Fig. 1, which may be located in any convenient position for observation by the attendant.

Referring now to Fig. 2, it will be seen that

the web photocell 20 has in circuit therewith a suitable source of potential 32, a resistance 34, and a condenser 36, so that, when its field of vision is interrupted by the register mark or target 18, a positive voltage impulse will be fed into the input circuit of a two stage amplifier 38. A suitable coupling condenser 40 and potentiometer 42 may, as indicated, be provided between the first and second stages of amplification so as to control the amount of amplification. The amplified pulse is led through conductors 44 and 46 into the grid circuit of a first gas-filled grid controlled electron discharge device 48, such as a conventional thyratron tube which will be referred to as the first thyratron. The conductor 44, which leads directly to the grid, has a condenser 50 and a suitable resistance 52 included therein for insuring complete loss of grid control when the plate discharge starts. Also included in the grid-cathode circuit of the first thyratron are a resistor 54 connected to the source of potential through a conductor 56, a condenser 58, and a potentiometer 60, which, through a conductor 62 connected to the source of potential through a switch 64, shown in operative position, create a sufficient negative bias on said thyratron that it normally has no plate current. Switch 64, due to the fact that its two terminals are connected to the voltage divider at different points, allows the negative bias on the thyratron to be increased while adjusting the amplification of the pulse so that, when said switch is in operative position, the pulse raises the grid voltage a predetermined amount above the discharge or firing point and the first thyratron immediately passes plate current. Thus, the switch 64 constitutes means for adjusting the peak value of the pulse to a standard or predetermined value sufficiently above the minimum operating voltage to insure reliability in operation.

The anode of thyratron 48 is connected through a conductor 70 with the winding of a first normally closed relay 72 having an upper contact 74, an armature 76, and a lower contact 78. From the winding of the first relay a conductor 80, having a resistance 82 therein, leads to the positive side of the source of potential. Hence, the passage of plate current from the first thyratron 48 will cause the first relay 72 to be energized, so that the armature 76 will move to the lower contact 78. This closes a circuit including a conductor 84 leading to one side of a source of alternating current, and a conductor 86 which passes through the green signal lamp 30 to the other side of the source of alternating current for said lamp.

At the same time that this action is taking place, the plate current from the first thyratron passing through a rheostat 88 starts to charge a condenser 90, in the grid circuit of a thermionic vacuum tube 92, such as a triode tube, which will hereinafter be referred to as the timing triode and has its cathode connected to the source of potential through a conductor 94. This condenser 90 is connected through a conductor 96 and resistance 98 to the grid of the timing triode and causes the grid voltage to become less negative. As this occurs, plate current will begin to flow from the anode of the timing triode through a conductor 100 to the winding of a timing relay 102 having a contact 104 and armature 106 which are normally closed and in the circuit of the conductor 80 leading to the source of potential. From the winding of relay 102, a conductor 108 also connects the relay to the conductor 80 lead-

ing to the source of potential. The plate current from the timing triode 92 continues to increase until the armature 106 of the timing relay 102 moves and thus cuts off the plate current of the first thyratron 48. I have found it desirable to shunt the contact 104 and armature 106 with a resistance 110 and condenser 112 which nevertheless are sufficient to prevent the plate current from passing when the timing relay is open. Such opening of the timing relay 102 causes the grid voltage of the timing triode to become more negative and drop its plate current until the timing relay closes and reconnects the plate circuit of the first thyratron.

The photocell 22, viewing the timing mark or notch 24 on the handwheel 14, likewise has in circuit therewith a suitable source of potential 114, a resistance 116 and a condenser 117, so that when the mark 24 on the handwheel causes a beam of light to be reflected thereto, a positive voltage impulse will be fed into the input circuit of a two stage amplifier 118. The amplified pulse is led through conductors 120 and 122 into the grid circuit of a second gas-filled, grid controlled electron discharge device 124, such as a conventional thyratron tube which will be referred to as the second thyratron. Conductor 122 leading directly to the grid of the second thyratron, similar to conductor 44 for the first thyratron, may also be provided with a condenser 126 and resistances 128 and 130. It will be noted that resistance 130, condenser 126 and potentiometer 60 also serve to create a sufficiently negative bias on the second thyratron 124 so that it normally has no plate current; but similarly to thyratron 48, the positive pulse from the amplifier 118 raises the grid voltage a fixed amount above the discharge point and said second thyratron immediately passes plate current.

Such plate current is fed through a conductor 132 to the winding of a second relay 134 having an upper contact 136, an armature 138, and a lower contact 140; and from the winding a conductor 142 having a resistance 144 therein leads to the conductor 80 which is connected to the source of potential as explained above. Energization of the relay 134 causes the armature 138, which is connected to conductor 84 through relay 72, to move to the lower contact 140 and thus closes a circuit including the conductor 84 leading to one side of the source of alternating current, and a conductor 146 leading through the red signal lamp 28 and to conductor 86 which is connected to the other side of the source of alternating current.

As with the first thyratron, the plate current from the second thyratron 124, while energizing its relay 134, also starts to charge the condenser 90 for the timing triode so that the timing relay 102 causes the plate current for the second thyratron to be cut off at the proper time.

It will be noted that the cathodes of the first and second thyratrons are interconnected by a conductor 148 which is connected through the potentiometer 60 with the conductor 62 leading to the source of potential so that the plate circuits for the two thyratrons are properly closed. This interconnection, however, has a further significance in my present arrangement; that is, when either of the thyratrons 48 or 124 is passing plate current, the bias on the grid of the other or idle thyratron will be increased negatively so that, after an adjustable time interval which is determined by the setting of the potentiometer 60, said other thyratron will be prevented from firing as

it normally would when a positive pulse is fed into its grid circuit. In this manner, whichever of the photocells is energized first, its associated signal light will be operated and the other will be prevented from operating until a correction of register is made. Adjustment of the timing triode 92 determines the length of time that the energized signal lamp will remain lighted for a single flash. It will be apparent that when both photocells are actuated substantially simultaneously, or within a certain desired time interval, both of the relays 72 and 134, associated therewith, will be energized, but due to the cross connections indicated in Fig. 2 neither signal lamp will be lighted.

As explained above, the switch 64 is provided to aid in the initial setting and adjustment of the apparatus, so that the desired and proper increment of bias may be obtained on the thyratrons. For further facilitating such initial adjustments and for limiting the amplitude of the pulse impressed on the grids of the thyratrons, I have inserted a diode tube 150 in the circuit. One anode of this tube is connected by a conductor 152 to the conductor 44 between the resistance 52 and the condenser 50; while the other anode is connected by a conductor 154 to the conductor 122 between the resistance 128 and the condenser 126. The cathode of the diode is connected through a conductor 156 directly with the source of potential at a point on the negative side of the switch 64. Hence, when the switch 64 is set initially, the diode tube, which has a positive potential between its cathode and anodes, will have the effect of cutting off any pulse passing to the thyratrons very slightly above the set increment of bias.

While I have described one specific embodiment of my invention as including certain definite elements, it will be understood that various changes may be made in the circuits, and certain features thereof may be employed without others, without departing from my invention or sacrificing any of its advantages.

What I claim is:

1. In apparatus for feeding a web through a plurality of conditioning units, at least one of which has an element operating in timed relation with the movement of a conditioning element of one of said units, means for indicating when the web is longitudinally out of register, said means comprising a first photo-electric cell controlled by the web; a second photo-electric cell controlled by the position of said operating element; two indicating devices; and circuit means associated with said photo-electric cells for actuating one or the other of said indicating devices when the web is out of register, said circuit means including a primary circuit for each of said photo-electric cells, and a vacuum tube for limiting the amplitude of the pulse passed from said photo-electric cells into said primary circuits.

2. In apparatus for feeding a web through a plurality of conditioning units, at least one of which has an element operating in timed relation with the movement of a conditioning element of one of said units, means for indicating when the web is longitudinally out of register, said means comprising a first photo-electric cell controlled by the web; a second photo-electric cell controlled by the position of said operating element; two indicating devices; and circuit means associated with said photo-electric cells for actuating one or the other of said indicating devices when

the web is out of register, said circuit means including a primary circuit for each of said photo-electric cells, and timing means interconnected with said primary circuits and including a vacuum tube and an electro-magnetic relay.

3. In apparatus for feeding a web through a plurality of conditioning units, at least one of which has an element operating in timed relation with the movement of a conditioning element of one of said units, means for indicating when the web is out of register, comprising a first photo-sensitive element adapted to be actuated in response to the light variations produced by a register mark applied to the web; a second photo-sensitive element adapted to be actuated in response to the light variations produced by a timing mark applied to said operating element; an indicating device; and circuit means associated with said photo-sensitive elements for actuating said indicating device when the web is out of register, said circuit means including a plurality of gas-filled, grid-controlled, electron discharge devices, and means for limiting the amplitude of the pulse impressed on the said electron discharge devices by the action of said photo-sensitive elements.

4. In apparatus for feeding a web through a plurality of conditioning units, at least one of which has an element rotating in timed relation with the movement of a conditioning element of one of said units, means for indicating when the web is out of register, comprising a first photo-sensitive element adapted to be actuated in response to the light variations produced by a register mark applied to the web; a second photo-sensitive element adapted to be actuated in response to the light variations produced by a timing mark applied to said rotating element; an indicating device; and circuit means associated with said photo-sensitive elements for actuating said indicating device when the web is out of register, said circuit means including a plurality of gas-filled, grid-controlled, electron discharge devices and a plurality of electro-magnetic relays.

5. In apparatus for feeding a web through a plurality of conditioning units, at least one of which has an element rotating in timed relation with the movement of a conditioning element of one of said units, means for indicating when the web is out of register, comprising a first photo-sensitive element adapted to be actuated in response to the light variations produced by a register mark applied to the web; a second photo-sensitive element adapted to be actuated in response to the light variations produced by a timing mark applied to said rotating element; an indicating device; and circuit means associated with said photo-sensitive elements for actuating said indicating device when the web is out of register, said circuit means including a thyratron tube associated with each of said photo-sensitive elements; an electro-magnetic relay associated with each of said thyratrons, and an interconnecting timing circuit.

6. In apparatus for feeding a web through a plurality of conditioning units, at least one of which has an element rotating in timed relation with the movement of a conditioning element of one of said units, means for indicating when the web is out of register, comprising a first photo-sensitive element adapted to be actuated in response to the light variations produced by a register mark applied to the web; a second photo-sensitive element adapted to be actuated in response to the light variations produced by a timing

mark applied to said rotating element; an indicating device; and circuit means associated with said photo-sensitive elements for actuating said indicating device when the web is out of register, said circuit means including a primary circuit for each of said photo-sensitive elements, and timing means interconnected with said primary circuits and including a vacuum tube and an electro-magnetic relay.

7. In apparatus for feeding a web through a plurality of conditioning units, at least one of which has an element rotating in timed relation with the movement of a conditioning element of one of said units, means for indicating when the web is out of register, comprising a first photo-sensitive element adapted to be actuated in response to the light variations produced by a register mark applied to the web; a second photo-sensitive element adapted to be actuated in response to the light variations produced by a timing mark applied to said rotating element; an indicating device; and circuit means associated with said photo-sensitive elements for actuating said indicating device when the web is out of register, said circuit means including a primary circuit for each of said photo-sensitive elements, and a vacuum tube for limiting the amplitude of the pulse passed from said photo-sensitive elements into said primary circuits.

8. In a multi-unit web printing press including a plurality of rotating printing members, means associated with at least one of said units for indicating when the web is longitudinally out of register, comprising a first photo-electric cell which is adapted to be actuated in response to light variations produced by a register mark applied to the web; a second photo-electric cell which is adapted to be actuated in response to light variations produced by a rotating timing mark associated with one of the rotating printing members; an indicating device; and circuit means associated with said photo-electric cells for actuating said indicating device when the web is out of register, said circuit means including a primary circuit for each of said photo-electric cells, a vacuum tube for limiting the amplitude of the pulse passed from said photo-electric cells into said primary circuits, and timing means interconnected with said primary circuits and including a vacuum tube and an electro-magnetic relay.

9. In combination with a web printing press having a rotating printing member, apparatus for indicating when the web is longitudinally out of register, comprising a first light sensitive element adapted to be actuated in response to light variations produced by a register mark applied to the web; a second light sensitive element adapted to be actuated in response to light variations produced by a rotating timing mark associated with said printing member; and circuit means associated with said light sensitive elements and including an indicator, a thyratron tube for each of said light sensitive elements, timing means, and means for limiting the amplitude of the pulse passed from the light sensitive elements into the circuit means and the thyratron tubes.

10. Apparatus for indicating when a moving web is out of register in the direction of its travel, comprising an element operating on said moving web; light sensitive means controlled by said web for producing an electrical impulse; a second light sensitive means controlled by the position of said operating element for producing a second electrical impulse; means actuated by said im-

pulses for indicating that the web is out of register when the interval between said impulses exceeds a predetermined amount; and means for limiting the amplitude of the impulses passed from said light sensitive means.

11. Apparatus of the character described, comprising an element operating on a moving web; light sensitive means controlled by said web for producing an electrical impulse; a second light sensitive means controlled by the position of said operating element for producing a second electrical impulse; and means actuated by said impulses for indicating that the web is out of register when the time interval between said impulses exceeds a predetermined amount, said means comprising a circuit for each of said light sensitive elements including a gas filled electron discharge device, and means for limiting the amplitude of the pulse passed from said light sensitive means into said circuits and electron discharge devices.

12. Apparatus for indicating when a moving web is out of register in the direction of its travel, comprising an element operating on said moving web; light sensitive means controlled by said web for producing an electrical impulse; a second light sensitive means controlled by the position of said operating element for producing a second electrical impulse; means actuated by said impulse for indicating that the web is out of register when the interval between said impulses exceeds a predetermined amount; and means for adjusting the peak value of the impulses to a predetermined value sufficiently above the minimum operating voltage to insure reliability in operation.

13. Apparatus for indicating when a moving web is out of register in the direction of its travel, comprising an element operating on said moving web; light sensitive means controlled by said web for producing an electrical impulse; a second light sensitive means controlled by the position of said operating element for producing a second electrical impulse; means actuated by said impulses for indicating that the web is out of register when the interval between said impulses exceeds a predetermined amount; means for limiting the amplitude of the impulses passed from said light sensitive means; and means for adjusting the peak value of said impulses to a standard value sufficiently above the minimum operating voltage to insure reliability in operation.

14. Apparatus for indicating when a moving web is out of register in the direction of its travel, comprising an element operating on said moving web; light sensitive means controlled by said web for producing an electrical impulse; a second light sensitive means controlled by the position of said operating element for producing a second electrical impulse and means actuated by said impulses for indicating that the web is out of register when the interval between said impulses exceeds a predetermined amount, said means comprising a circuit for each of said light sensitive elements including a gas filled electron discharge device, and means for adjusting the peak value of the impulses to a predetermined value sufficiently above the minimum operating voltage to insure reliability in operation.

MORRIS SORKIN.
